UNITED STATES PATENT OFFICE.

JOHN SPEIRS, OF JERSEY CITY, NEW JERSEY, ASSIGNOR OF ONE-HALF TO
GEORGE FRANKLIN RICHARDSON, OF NEW YORK, N. Y.

COMBINED DIVING APPARATUS AND LIFE-SAVING RAFT.

SPECIFICATION forming part of Letters Patent No. 449,354, dated March 31, 1891.

Application filed May 23, 1890. Serial No. 352,963. (No model.)

To all whom it may concern:

Be it known that I, JOHN SPEIRS, a citizen of the United States, and a resident of Jersey City, in the county of Hudson and State of New Jersey, have invented a certain new and useful Diving and Life-Saving Apparatus, of which the following is a specification.

My invention relates to a combined diving apparatus and life-saving raft, the object being to make a device whereby the bottom of floating vessels may be approached for repairs or cleaning, without danger to life or exhaustion from pressure of condensed atmosphere, and which in case of emergency by the simple addition of a cap may be made into a life-raft, and when not in use may be folded together, so that it will occupy but little space.

To enable others to make and use my improved apparatus, I will give a description of the same in detail, reference being had to the drawings hereto annexed.

Figure 1 is a view of the device partly in section and of a portion of a vessel, and shows the position of the device making repairs on the rudder. Fig. 2 shows the apparatus partially folded together. Fig. 3 shows the device suspended from davits on the side of the vessel. Fig. 4 shows the cap which is used when the device is prepared for a life-raft. Fig. 5 is a perspective view showing two of the apparatus fastened together to make a life-raft.

The body A of the apparatus is made of canvas or other flexible material impervious to water, and in the form of a hollow cylinder. The end which is used for the bottom is closed air-tight by a conical cap B, made preferably of metal. At the apex of the cone B a ring a is fixed, into which ropes are fastened, by which the bottom of the device is drawn toward the vessel by passing said ropes underneath the keel and up the opposite side, as shown in Fig. 3. The ring a is also used to secure the two apparatus together for the life-raft, as shown in Fig. 5.

At the sides of the cone or cap B are rings b, into which ropes c are fastened.

The upper end of the canvas cylinder is clamped between two bands d and e. The inner band e, which is threaded to receive the cap B, Fig. 4, also has rings into which the rope lad-

der C is fastened. The outer band d has rings in it into which the ropes c are fastened. The ropes are the supports by which it is suspended from the davits and form the life-lines when the device is used for a life-raft. Rings may 55 be fastened to the ropes c, which serve as fenders to keep the device from chafing against the vessel.

At the proper distance from the bottom in the side of the canvas a window F is fixed, 60 and a short distance below the window, on each side, is a sleeve D, made in one piece with gloves and secured water-tight to the body A, into which the operator slips his arms and hands, as shown in Fig. 1.

Ballast is put in the bottom of the device to sink it to the required depth.

On the inside of the canvas are several rigid hoops E, fastened to it, which keep the cylinder from being crushed in by the pressure of 70 the water.

K are hoops on the outer side of the cylinder to support it against outward strain.

The cap B', Fig. 4, is similar to the cap B, Fig. 1, and has a shoulder and a threaded part 75 f, which screws into the threaded band e, Fig. 1. A gasket g is used between the shoulder of the cap and the edges of the bands d and e to insure an air-tight joint.

When the apparatus are used for a life-raft, 80 they are drawn out to the full length and the caps B' screwed home, making air-tight cylinders not unlike in form to those now in use for the same purpose. Two or more of the apparatus may be secured together by ropes 85 passing through the rings a and a'. When not in use, the apparatus is closed up by folding it longitudinally, as shown in Fig. 2.

The tools h, which are ordinarily used for work under water, are hung by chains to the 90 outside of the tube within reach of the arms.

Having described my invention and its use, what I claim as new, and desire to secure by Letters Patent, is—

1. A convertible diving and life-saving apparatus, the same comprising a flexible tube provided with bracing-hoops, caps for closing each end of the tube, one of said caps being removable, rings at the apexes of the caps, and ropes or stays passing through the rings 100

for securing the tube to the side of a vessel or to another tube of similar construction, substantially as set forth.

2. A flexible tube A, provided with rings 5 inside and outside and permanently closed at one end by cap B, and having arms D and window F, in combination with the cap B'.

3. The combination of the tube, closed at one end by the cap B, constituting the floor, 10 and having a threaded band e at the opposite

end, with the flexible arms D above the floor window F, and the ladder C.

Signed at New York, in the county of New York and State of New York, this 20th day of May, A. D. 1890.

JOHN SPEIRS.
